GAS SEPARATOR

David Rosenberg, 12 Francis Court,
Glen Cove, N.Y. 11542

Filed Apr. 10, 1969, Ser. No. 16,671

Term of patent 14 years

Int. Cl. D23—04

U.S. Cl. D23—149

FIG. 1

FIG. 2

FIG. 4

FIG. 3

FIG. 1 is a top view of a gas separator showing my new design;

FIG. 2 is a bottom view thereof;

FIG. 3 is a perspective view thereof, and

FIG. 4 is a side view thereof.

The claimed design is shown in full lines in the drawing. The fragmentary broken lines showing fluid connecting lines in FIGS. 1, 2, 3 and 4 are for illustrative purposes only to show the overall configuration of the article in which the claimed design is incorporated.

I claim:

The ornamental design for a gas separator, as shown and described.
